(57) **CLAIM**

The ornamental design for an absorbent pet pad.

DESCRIPTION

FIG. 1 is a top perspective view of an absorbent pet pad. FIG. 2 is a top view of the absorbent pet pad of FIG. 1. FIG. 3 is a left side view of the absorbent pet pad of FIG. 1 the right side view is identical. FIG. 4 is a front view of the absorbent pet pad of FIG. 1. The back view is identical. FIG. 5 is a bottom view of the absorbent pet pad of FIG. 1; FIG. 6 is a cross-sectional view taken along line 6-6 on FIG. 2; FIG. 7 is a top perspective view of second embodiment of an absorbent pet pad. FIG. 8 is a top view of the absorbent pet pad of FIG. 7. FIG. 9 is a left side view of the absorbent pet pad of FIG. 7. The right side view is identical. FIG. 10 is a front view of the absorbent pet pad of FIG. 7. The back view is identical. FIG. 11 is a bottom view of the absorbent pet pad of FIG. 7; and, FIG. 12 is a cross-sectional view taken along line 12-12. The absorbent pet pad is shown with breaks in its width. The appearance of any portion of the article between the break lines forms no part of the claimed design.

1 Claim, 4 Drawing Sheets
